UNITED STATES PATENT OFFICE.

THOMAS L. HARTMAN, OF PITTSBURGH, PENNSYLVANIA.

TEMPERATURE-EQUALIZING COIL.

1,331,429.

Specification of Letters Patent.

Patented Feb. 17, 1920.

Application filed November 2, 1917. Serial No. 199,847.

To all whom it may concern:

Be it known that I, THOMAS L. HARTMAN, a citizen of the United States, residing at Pittsburgh, in the county of Allegheny and 5 State of Pennsylvania, have invented certain new and useful Improvements in Temperature-Equalizing Coils, of which the following is a specification.

My invention relates to the art of making 10 temperature equalizing coils of the class used in refrigerating apparatus and for heating or cooling purposes generally. The invention consists in the method of assembling the inner and outer circulating pipes 15 with an intervening concentric space, providing means for bending the said pipes together while maintaining their operative relations, and in the resulting product of such operation, having the several features of 20 novelty and advantage hereinafter set forth.

In the drawings illustrating certain preferred forms of the apparatus, and its manner of manufacture:

Figure 1 is a view in elevation of a series 25 of continuous return bend sections, in operative position.

Fig. 2 is an enlarged sectional detail view 30 of an inner and outer pipe section, partly broken away, prepared for bending.

Fig. 3 is a detail view, partly in section, 35 of the return bend portion of the compound pipe.

Fig. 4 is a similar view showing the pipes provided with a nipple connection.

Fig. 5 is an enlarged sectional detail view 40 showing the manner of applying the nipple.

Fig. 6 is a sectional detail view illustrating the manner of welding the ends of the outer pipes together and of providing the 45 spacing connection for the inner pipe.

Fig. 7 is a cross section on the line VII, 50 VII, of Fig. 6.

Fig. 8 is a detail sectional view of the ends 55 of the outer pipe prior to welding.

Fig. 9 is a similar view of the inner pipe 60 ends.

In carrying out my invention the inner pipe 2 is arranged within the outer pipe 3, while straight, and in suitable lengths to 65 provide the finished length desired, with an intervening concentric space 4. The inner pipe projects beyond each end of the outer pipe as shown and is held in fixed relation thereto by a packing or ring 5 of waste or 70 other suitable substance.

The space 4 is filled with sand or other suitable material, which is tamped or packed compactly by a pneumatic hammer or otherwise so as to provide a comparatively tight resisting body, adapted to resist the pressure 60 of the outer pipe in bending and to maintain the pipes in true concentric relation at all times during the bending operation.

The pipes as thus assembled are heated at those portions where they are to be bent and are then bent around a former or mandrel by suitable means, providing the loop ends 65 6, Fig. 1, and when this operation is completed, the sand is removed by air pressure or otherwise.

At one stage in the operation, before bending, I provide interior bracing and supporting loop rings 7 which are welded to the outer pipe 3 through suitable openings therein. This may be conveniently done by 70 inserting the thin connecting tongue or band 75 8 forming the ring between the adjacent ends of outer pipe sections 3, 3, or in suitable clearance notches therein, before these ends are welded together, thereby holding 80 the inner pipe in fixed relation to the outer pipe. In such welding connection, the outer pipe ends are interiorly scarfed as at 9 so that when the ends are heated and brought together under pressure, they will be joined 85 with substantially flush interior surfaces and any surplus metal will extend outwardly in the form of an annular ridge 10.

The inner pipe ends are similarly joined 90 by welding but with male and female scarfed 95 terminals 11, 12, which will interfit and provide smooth surfaces both inside and outside.

At other points than at the welded joints, the band rings 7 are introduced through a 95 sufficiently large opening in the outer pipe 3 by one end which is passed around the inner pipe 2 and is then again passed or "fished" through the outer pipe. The ends are brought together, with just sufficient gripping tension to hold the inner pipe centrally 100 of the outer, and the free ends are then welded to the outer pipe and the hole is closed, as indicated at a Fig. 2.

This operation is performed while the 105 pipes are straight, before bending, care being taken to locate the rings at proper distances apart to uniformly hold the inner pipe in position throughout the length of the entire series of return bend sections. 110

- Also, the attachments should be made at the side of the outer pipe 3 which is to be its upper side when the pipes are finally arranged in position, as in Fig. 1, which would be 5 alternating positions at the bending locations, so as to always support the inner pipe from the upper wall of the outer pipe, and prevent it from sagging. By this means I insure the continued concentric relations of 10 the pipes and free circulation space between them, and the supporting loops 7 are made of comparatively thin band metal, so as not to appreciably reduce the circulating cross area.
- 15 At any suitable point or points in the rounded or return bend portions 6 of the pipe I provide one or more cleaning nipples 13 for each bend extending inwardly through the outer and inner pipe and welded to each, 20 as shown. In this feature, I cut through both pipes, as by the oxyacetylene flame, leaving a somewhat enlarged hole 14 in the outer pipe, and am thus able to insert the nipple and to weld it to the inner pipe from the outside. Afterward the enlarged hole is 25 filled, the joint is finished, and the projecting threaded end of the nipple is covered by a cap 15.
- At each end the outer pipe 2 is then provided with a lateral connection 16, 17, for 30 gas connection and liquor connections, respectively, and the ends 18 of the inner pipe are threaded for connection with the water circulation pipes.
- 35 The series of pipe lengths are mounted in position by a holding rack or frame 19 of suitable construction, and it will be understood that any desired number of series may be used, or that the length and capacity of 40 the pipe may be varied as desired to suit the expected capacity or other requirements.
- The advantages of the invention will be readily understood and appreciated by all those familiar with this class of apparatus. 45 Because of the inner pipe being completely inclosed within the outer pipe throughout its entire length I avoid any exposure at the bends, thereby greatly increasing condensing efficiency, under all conditions and independently of local conditions as to temperature. All leaky joints are eliminated due to the absence of threaded or packed connections, by using the electrical welding process, and it is comparatively easy to test 50 the pipe with regard to its fluid-tight condition by compressed air or water. Because of the bends 6 being practically half circular and of uniform maximum diameter, friction of the traversing fluids is reduced to a mini-

mum, greatly adding to the efficiency of refrigerating or similar apparatus.

The advantages due to the novel method of bending greatly contribute to the symmetrical and fixed relations of the inner and outer pipes, assisted by the supporting rings 65 7, and there is always an even regular distribution of ammonia around the water pipe.

What I claim is:—

1. A temperature equalizing coil consisting of continuous inner and outer concentrically spaced pipes bent to provide a concentric wall return bent at intervals, and provided with spaced individual holding rings embracing the inner pipe with clearance for circulation and having an attaching terminal extending through and in fixed connection with the outer pipe. 70

2. A temperature equalizing coil consisting of continuous inner and outer concentrically spaced pipes bent to provide a return 80 bend at intervals, the inner pipe having a series of tightly embracing holding rings each having a laterally projecting portion extending through and fixedly connected with the outer pipe whereby to hold the inner and outer pipes in fixed concentric relation with an intervening annular circulation space therebetween. 85

3. A temperature equalizing coil consisting of a continuous inner and outer concentrically spaced pipe bent to provide a return bend, and having a nipple extending into the interior and welded to each pipe. 90

4. A temperature equalizing coil consisting of continuous inner and outer concentrically spaced compound pipes composed of annularly scarfed electrically welded sections, the inner and outer sections being uniformly spaced apart providing a concentric circulation opening throughout the entire 100 coil, and provided at intervals with a ring surrounding the inner pipe and having a terminal extending through and secured to the outer pipe. 95

5. A temperature equalizing coil consisting of a continuous inner and outer concentrically spaced compound pipe composed of electrically welded sections, the inner and outer sections being spaced apart providing a concentric circulation opening and provided with concentric wall return bend loops at intervals, and having isolated connecting devices secured around the inner pipe and through the wall of the outer pipe. 105

In testimony whereof I hereunto affix my 110
signature. 115

THOMAS L. HARTMAN.
